US0D1109206S

(12) **United States Design Patent** (10) **Patent No.:** **US D1,109,206 S**
(45) **Date of Patent:** **** Jan. 13, 2026**

(54) **TRANSMISSION MOCK-UP ASSEMBLY**

(71) Applicant: **Speedway Motors, Inc.**, Lincoln, NE (US)

(72) Inventor: **Mike Ahlquist**, Lincoln, NE (US)

(73) Assignee: **Speedway Motors, Inc.**, Lincoln, NE (US)

(**) Term: **15 Years**

(21) Appl. No.: **29/968,332**

(22) Filed: **Oct. 16, 2024**

(51) LOC (15) Cl. **15-99**

(52) U.S. Cl.

USPC **D15/149**; D15/5

(57) **CLAIM**

The ornamental design for a transmission mock-up assembly as shown and described.

DESCRIPTION

FIG. 1 is a perspective view of the transmission mock-up assembly.

FIG. 2 is a left view of the transmission mock-up assembly.

FIG. 3 is a right view of the transmission mock-up assembly.

FIG. 4 is a top view of the transmission mock-up assembly.

FIG. 5 is bottom view of the transmission mock-up assembly.

FIG. 6 is a front view of the transmission mock-up assembly; and,

FIG. 7 is a back view of the transmission mock-up assembly.

1 Claim, 7 Drawing Sheets
